DEVICE FOR SUPPORTING GLASS DURING HEATING

Theodore William Glynn, Kingsport, Tenn., assignor to Blue Ridge Glass Corporation, Kingsport, Tenn., a corporation of New York

Application October 6, 1947, Serial No. 778,167

1 Claim. (Cl. 49—14)

1

In the production of tempered glass it is necessary to heat the glass to near the softening point. During the period of such heating it is necessary to support it to prevent its distortion and this by means not injurious to the surface or introducing strain.

With this end in view it has been the general practice to hang flat glass sheets vertically by tongs, the prongs of which enter to a slight extent the surface of the sheet near the upper edge thereof. Under this arrangement the pull of gravity is relied on to prevent distortion of the sheet, but it has been found that the prong entrance into the sheet results, on the cooling of the sheet, of introducing strains tending to weakness.

I propose therefore, according to this invention, to rest the sheet in stirrups and to hold the sheet vertically by metallic wires on each side thereof held taught by weights, the wires so positioning the stirrups in relation to the lower edge of the sheet as to reduce to a minimum the distortion of the latter due to its gravity.

Referring to the accompanying drawings, in which corresponding parts are designated by corresponding marks of reference—

Figure 1 is an elevation of a glass sheet supported in accordance with this invention.

Figure 2 is an end view thereof.

In these drawings I have designated by A a sheet of glass, say 16" by 24" by $\frac{1}{4}$ " (the major axis vertical) which is to be heated.

1 is a bar on which are carried the hangers 2, from each of which is pendent a pulley 3. The bight of a nichrome or other heat resistant wire 4 passes over each of the pulleys and has its lower ends passed through a spreader 5 on the upper end of a standard 5a arising from a weight 5b, say of 20 pounds. The spreaders are functionally parts of the weight. The two ends of the wire in passing through a spreader are held apart a distance substantially equal to the thickness of the plate, while a washer 6 having an opening of about $\frac{1}{4}$ " is threaded over both runs of each wire above the plate.

Supported on each spreader is a knife edge 7 on which the sheet rests.

I have found that sag of the medial portion of a soft sheet may be prevented by spacing a knife edge at a distance from each vertical edge of the plate equal to about $\frac{1}{6}$ of the length of the bottom edge or at a distance apart equal to 66% of the length of such lower edge. There is, however, with this spacing a tendency of the

sheet to distort at its top between the wires and to prevent this I prefer to move the knife edges closer together by an amount equal to about $\frac{1}{6}$ of that resulting from the spacing above specified, thus making the distance apart of the edges about 60% of the length of the lower edge of the sheet.

2 To permit the distance between the knife edges to be adjusted to meet the above conditions with 10 the sheets of varying width I prefer to provide for a shifting of the hangers on their carrying bar and clamping thereon in the desired positions. This may be done by passing the bar through slots in the hangers and providing friction clamps 15 controlled by pressure screws 8 bearing on the top of the bars. As shown the lower end of the hangers terminate in claws 2a for receiving the pin 3a in the upper end of the yokes 3b in which the pulleys are mounted.

20 In the use of my invention the hangers having been properly positioned on the bars with the pulleys and wires and weight depending therefrom the sheet is inserted between the two runs of the wire and the washers are allowed to drop 25 close to the upper edges of the sheet. The sheet thus supported from the bar is inserted in a suitable heating furnace. Upon completion of the heating it is removed from the furnace while still dependent from the bar to receive subsequent treatment, such as chilling.

30 Having thus described my invention, what I claim is:

In a device for supporting a glass sheet vertically during heating, the combination with 35 35 knife edges below the bottom of the sheet, a vertical run of wire on each side of the sheet supporting the said knife edges, a weight pendent from said wires, pulleys over which the said runs of wire pass, a carrying bar and brackets 40 movable on said bar and means for clamping the brackets to the bar.

THEODORE WILLIAM GLYNN.
